UNITED STATES PATENT OFFICE

CHARLES GILBERT HAWLEY, OF CHICAGO, ILLINOIS, ASSIGNOR TO CENTRIFIX CORPORATION, OF CLEVELAND, OHIO, A CORPORATION OF OHIO

CENTRIFUGAL STEAM CONDITIONER

Application filed January 31, 1931. Serial No. 512,721.

This invention relates to improved means for removing entrained substances such as moisture and solids from steam and like pressure fluids. The object of the invention is to provide a non-rotative fluid departure head or fixture through which the pressure fluid must find its escape from the pressure vessel or pipe line containing it; and which, though of non-rotative character, shall effect the centrifugal separation of the entrained substances; and, the ejection thereof; utilizing the movement of the pressure fluid as a means to that end. The more specific objects of the present invention will appear in detail hereinafter; and, the invention being of a simple kind easily understood from drawings, immediate attention is directed to those drawings which form part of this specification, wherein the invention is clearly set forth.

In said drawings, Fig. 1 is a sectional elevation of a steam drum or like pressure vessel containing steam conditioning or purifying fixtures which embody the present invention;—Fig. 2 is a cross section thereof, on the line 2—2 of Fig. 1;—Fig. 3 is a similar cross section showing the manner in which the conditioner is modified for use upon a steam exit pipe that passes through the bottom of the drum;—Fig. 4 is an enlarged top view of a complete conditioner or fixture of the open type;—Fig. 5 is a vertical section thereof on the line 5—5 of Fig. 4;—Fig. 6 is a detail illustrating the manner in which the whirl-promoting tuyère of the fixture is keyed or locked in the body of the conditioner;—Fig. 7 is a compound horizontal section, one-half upon the line 7—7 and one-half upon the line 7a— of Fig. 5;—Fig. 8 is a side elevation of the conditioner with its upper part broken away, the better to disclose the construction of its whirl-producing tuyère;—Fig. 9 is a vertical section of a modified form of the invention suited to the incorporation therewith of a whirl-producing tuyère of another type;—Fig. 10 is a sectional view thereof on the line 10—10 of Fig. 9;—and, Fig. 11 illustrates one form which the invention may take when adapted for inclusion in pressure fluid pipe lines, such as steam and gas lines.

Fixtures like those shown in Figs. 1 to 10,

inclusive, are of the downflow type, and hence in applying them to the dry pipes or outlet pipes of steam drums 2 and the like, they are placed upon the upturned ends of such pipes. The pipes may lead either laterally or upward or downward through the shell of the boiler or other pressure vessel, as most convenient, and the fixture embodying this invention provides the avenue through which the pressure fluid moves when departing from the latter. The relation here described is well illustrated in Figs. 1 and 2 by the dry pipe 3 having two upturned ends 4—4 to each of which a centrifugal purifier or conditioner A is applied. The dry pipe 5 of Fig. 3 is normally open at its upper end and there is equipped with the purifier or conditioner.

Details of construction will presently be explained and meantime it suffices to state that the top of the purifier or fixture is occupied by an element called a whirl-promoting tuyère which comprises the entrance for the pressure fluid. The presence of the tuyère causes the passing fluid to whirl rapidly within the fixture before entering the open dry pipe. In consequence of the whirling action the substances are entrained in the pressure fluid and centrifugally separated within the body of the fixture A, and are collected in the lower part of the fixture, whence they are then drained or ejected into the lower part of the pressure vessel through open ended drain pipes, such as the pipes 6.

Considerable energy is exercised and consumed in whirling the fluid within the fixture as here stated; and, special protective means must be adopted to avoid within the fixture a drop of pressure of a magnitude which would defeat the return or ejection of the separated substances from the base of the fixture. Further means must be adopted to ensure a minimum drop of pressure as between the exterior of the pressure vessel and the outlet or dry pipe, for any considerable loss of pressure within the fixture would be reflected in a noticeable and objectionable difference of pressure inside and outside of the main pressure vessel. Again the velocity at which the pressure fluid whirls and sweeps

through the fixture, makes it difficult to prevent the re-entrainment of substances which are first successfully separated therein. This invention, therefore, centers upon the accomplishment of the purification or conditioning of the outgoing fluid at little cost of pressure and with an assured collection and ejection of the centrifugally separated substances, and likewise stresses the sure return of those substances to the body of the pressure vessel from which they were originally removed by the outflowing pressure fluid. This last may be ignored to some extent when an automatic trap is available for the external discharge of the collected substances, but even then it is extremely desirable to provide a fixture, which through entailing little loss of pressure within itself, is capable of promptly and continuously discharging the separated liquid or solids or both. These objects are admirably attained in and by the invention illustrated in the accompanying drawings.

A conditioner or fluid purifying fixture of the kind illustrated in Figs. 4 to 8, inclusive, is characterized by a substantially cylindrical body portion, *a*, which contains the smaller and central downflow nozzle *a2* leading from its bottom *a'* and providing the fluid outlet or orifice of the internal separating space *a3*.

The open upper end of the shell or body, *a*, is internally bored and shouldered to receive and contain the peripheral ring portion *a4* of the whirl-promoting tuyère above mentioned. In addition to said ring, the tuyère comprises a circumferential series of tangential or inclined radial blades *a5*, together with a central portion or hub *a6*. Specifically, the part *a4* and *a6* are made of cast metal while the blades *a5* are composed of wrought metal and the ends thereof are embedded in the parts *a4* and *a6* at the time they are formed in the metal casting mold. Such radially bladed structure is both rigid and rugged, and it provides as many downward leading inclined tuyère openings *a5'* as it has blades *a5*. The combined area of these tuyères exceeds that of the orifice to avoid possibility of wire drawing the passing fluid which would result in a positive loss of pressure. The tuyère is held against rotary movement in the body, *a*, as by a locking notch and pin *a7* and *a8*, which however, do not prevent the removal of the tuyère from the shell.

The tuyère is completed by a thin walled conical member *a9* which occupies the lower end of the hub portion *a6*, wherein it is secured by a rivet *a10*. The large diameter of the cone *a9* substantially equals that of the orifice *a2* and it is positioned axially opposite the same; and is widely spaced therefrom across the separating chamber *a3*. The area of the annular opening remaining between

the edge of the cone and the edge of the orifice greatly exceeds the area of the orifice.

It will at once be noted that the bottom of floor *a'* is positioned far below the top of the orifice standpipe or sleeve *a2* and that the separating chamber *a3* has a bottom portion *a11* (which is far above the bottom *a'*) thus creating the centrifugal collection compartment or annular cistern *a12*. The portion *a11* is in the nature of a flange which extends inward and downward from the inner surface of the cylindrical wall of the body portion, *a*. By preference, it is in one piece therewith. The inner periphery *a11* of the flange *a11* is positioned below the top of the part *a2* and therewith defines a wide annular opening *a13* at the bottom of the chamber *a3*.

As best defining its function the portion *a11* will be referred to as a whirl damping flange and it plays a most important part both in aiding the separation of entrainment and in preventing the reentrainment of substances which have once been separated from the pressure fluids.

The inner surfaces of portions *a* and *a11* merge smoothly, sudden shoulders at the juncture thereof being avoided. By preference, the bottom surface *a14* of the separating bowl or chamber *a3* is curved as here shown and in every case the bottom contains the large central opening *a13* which encloses the orifice riser or sleeve *a2*.

By preference, though not of necessity, the top of said riser *a2* is marked by the conical or flaring surface *a16* which leads the purified fluid into the orifice *a2*. In every case it is preferred that the exterior of the part *a2* shall present the surface *a18* which rises above the inner edge *a11'*, of the bowl bottom *a11*, thence pitching downward and inward to a juncture with the lower part of the riser *a2*.

The bottom *a'* is marked by the raised shoulder *a19* at the base of the riser *a2*, beneath the opening *a13*. An annular retention groove *a20* is thus formed in the outer bottom portion of the annular cistern *a12*. The substances which collect in the cistern are promptly discharged through the hollow elbow or projection *a21* which contains the upper end of the before mentioned eject pipe, *a6*. As well shown in Fig. 1 the lower end *a6* of the drain pipe opens into the liquid in the boiler or drum *a2*.

As indicated in Figs. 8 and 9, the downwardly extending end *a2'* of the part *a2* may be variously shaped to suit its attachment to the particular dry pipe which supports the fixture.

Assuming the fixture to be in position within an active steam boiler, as shown in Fig. 1, the steam will enter it by passing downward through the tangential or angular tuyères *a5'* surrounding the hub *a6*. Its entry to the cylindrical chamber *a3* is marked

By the consequent whirling of the steam as it moves toward the orifice offered by the open central riser a_2 or orifice. The moisture carried by the steam is centrifugally deposited upon the inner surface of the body, a , and further the steam presses against that wall as it whirls downward in the chamber and toward said orifice. The whirl damping flange a_{11} performs the function of limiting the longitudinal freedom of the whirl and accentuating the collection of the moisture in the bottom corner of the chamber, distant from the outlet orifice. Meantime, the whirling steam, in order to escape, is forced to sweep inwardly in order to reach that outlet; and thus the momentarily collected liquid is urged toward the opening a_{13} and falls or whirls downward into the cistern a_{12} . That cistern is constantly drained as explained; and in this way the collected liquid is prevented from reaching the outlet of the fixture. As a further precaution the flange a_{11} is made to overhang the upper part of the cistern and the partial void created beneath the flange facilitates the retention of the moisture in the outer part of the cistern.

Due to the position of the top of the riser a_2 in the path of the inwardly sweeping steam, the whirling currents encounter or abut that part and must needs surmount the same to enter the orifice. Thus the liquid is certain to be thrown into the cistern and this relation is aided by the presence of the angular directing flange a_{18} opposite the edge a_{11}' of the bowl. Further and importantly these relations of the parts to the whirling fluids result in maintaining maximum high pressures within the cistern a_{12} . It will at once be recognized that such high pressure makes the direct return of the moisture to the boiler a safe proceeding. Except for this high pressure in the cistern and eject pipe 6, it would be necessary in all cases to discharge the moisture through drains and traps external to the boiler, a practice that entails the loss of the heat in the intercepted water.

Some moisture particles carried by the steam are too minute to yield promptly to the centrifugal action described and it is for this reason that the conical part a_9 is of importance. Particles which impact the blades a_5 are safely massed thereon and are delivered to the inner wall of the fixture but other particles tend to remain in suspension in the central portion of the whirling body or vortex generated within the body by the presence of the tangential tuyère. Obviously, the pressure at the axis of the vortex is slightly less than that within the outer part of the chamber a_3 and as the steam sweeps past the extended edge of the cone, many stray particles are released and expelled or displaced toward the axis and are caught in the partial void existing beneath

said cone. Collecting in masses upon the under surface of the cone, the stray liquid takes on the whirling action of the vortex and is expelled tangentially, thus joining the other liquid collections upon the inner surface of the bowl or body, a .

The effect of this vortex defeating cone or element (a_9) is very positive. In further explanation it may be pointed out that the small or stray quantities of substance which reach and pass the edge of the cone as the result of whirling motion toward the outlet orifice are caught in the void occasioned by the presence of the cone within the vortex or whirling body of fluid, such particles being displaced inwardly by the streams of carrier fluid whirling toward the outlet. The individual particles, because of lack of mass, are intercepted and temporarily held on the inner margin of the conical cup; and, as the individual particles become agglomerated with others and attain sufficient mass they are centrifugally expelled from the inner margin of the cone, being there under the influence or impulsion of the vortex. Thus stray particles which escape accumulation in the major operation within the fixture and which might otherwise escape along the axis of the vortex are thus positively intercepted as they approach that axis and are centrifugally expelled toward and into the outer parts of the fixture, where they are absorbed into and disposed of along with the major accumulations or masses of separated substances.

Incidentally, it is to be noted that the construction of the cone a_9 as a separate part is most advantageous from the standpoint of manufacture. As shown, it becomes a fixed part of the hub a_6 yet does not interfere with or complicate the casting thereof. The sink a_9' of the apex of the cone, while apparently a receptacle for moisture, ensures the expulsion of moisture from the axis of the cone and thus prevents its escape into the orifice along that axis.

In addition to the advantages above named, this fixture has the obvious advantages of great simplicity, of the ready accessibility of all its internal surfaces, of a low altitude which enables its use in small steam spaces, of low cost, and is easy of installation. Further, the fixture is wholly self cleaning and once installed requires no attention to keep it in operating condition.

Lest it be thought that the invention is limited to a tuyère of the radial type above detailed, a substitute tuyère of a barrel type has been depicted in Figs. 9 and 10. The use thereof entails an increase of height but otherwise the body and bottom portions of the fixture remain as before described. For this reason the same reference letters are applied to those parts.

The whirl promoting tuyère of Figs. 9 and 10

10 comprises a top ring, *b*, which is large enough to close the otherwise open top of the bowl, *a*. That ring, *b*, contains a central hole, *b'*, which, to ensure virtual freedom 5 from pressure drop, is of greater area than the fixture orifice *a2*. Depending from the ring, *b*, is a circumferential series of tangentially positioned blades *b2* and the lower ends of those blades support the bottom forming 10 cone *b3*. By preference, the parts *b* and *b3* are cast upon the ends of the blades *b2* in the manner before described in speaking of the parts of the radial type tuyère.

The aggregate area of the tangential tuyères *b4* greatly exceeds the area of the orifice *a2* and the fluid enters the chamber *a3* against little resistance. But it is nevertheless directed outward against the opposed wall of the bowl and is caused to rotate in 15 the chamber *a3* with sufficient velocity to accomplish the before described centrifugal separation of the entrained substances.

That this invention is capable of embodiment within a heavy walled pipe or line fixture is made evident by Fig. 11. Except for the preferred incorporation of a more capacious cistern portion, *c*, and the use of the flanged casing parts *c'* and *c2* the internal constructions remains as before described 20 and this closed type fixture operates in the same manner. This line fixture may also be used successfully upon a horizontal axis and, by the extension of the eject nozzle *c3* from the opposite side of the cistern portion, may 25 even be adapted for use in an inverted or upgoing position.

Having thus described my invention, I claim as new and desire to secure by Letters Patent:—

40 1. A non-rotative centrifugal fixture adapted to separate entrained substances from fluid moving therethrough and comprising a separating bowl which is open at the top and has in its lower part a drain and 45 a centrally positioned outlet element, the latter rising from the bottom of the bowl, in combination with a whirl-promoting tuyère occupying said top of the bowl and forming its fluid inlet, and, said bowl containing an 50 inwardly and downwardly pitched whirl-damping flange that is positioned above its bottom and which terminates short of and below the top of said outlet element.

2. A non-rotative centrifugal fixture 55 adapted to separate entrained substances from fluid moving therethrough and comprising a separating bowl which is open at the top and has in its lower part a drain and a centrally positioned outlet element, the latter rising from the bottom of the bowl, in combination with a whirl-promoting tuyère occupying said top of the bowl and forming a fluid inlet of greater effective area 60 than said outlet and, said bowl containing 65 an inwardly and downwardly pitched whirl-

damping flange that is positioned above its bottom and terminates short of and below the top of said outlet element.

3. A non-rotative centrifugal fixture 70 adapted to separate entrained substances from fluid moving therethrough and comprising a separating bowl which is open at the top and has in its lower part a drain and a centrally positioned outlet element, the latter rising from the bottom of the bowl and having a flaring top, in combination with a whirl-promoting tuyère occupying said top of the bowl and forming its fluid inlet, and, said bowl containing an inwardly and downwardly pitched whirl-damping flange that is positioned above its bottom and terminates short of and below the flaring 75 top of said outlet element.

4. A non-rotative centrifugal fixture 80 adapted to separate entrained substances from fluid moving therethrough and comprising a separating bowl which is open at the top and has an annularly grooved bottom which contains a drain opening, in combination with an outlet element rising centrally from the bottom of the bowl, a whirl-promoting tuyère occupying said top of the bowl and forming its fluid inlet, and, said bowl containing an inwardly and downwardly pitched whirl-damping flange that is positioned above the 85 groove in its bottom and which terminates short of and below the top of said outlet element.

5. A non-rotative centrifugal fixture 90 adapted to separate entrained substances from fluid moving therethrough and comprising a separating chamber which is open at the top and has an annularly grooved bottom which contains a drain opening in combination with an outlet element rising centrally from the bottom of the bowl, a whirl-promoting tuyère occupying the top of said bowl and forming its fluid inlet, vortex-defeating means associated with said whirl-promoting tuyère, and an inwardly and downwardly pitched whirl-damping flange positioned above the groove in its bottom and terminating short of and below the top of said outlet element.

6. A non-rotative centrifugal fixture 100 adapted to separate entrained substances from fluid moving therethrough and comprising a separating chamber which is open at the top and has an annularly grooved bottom which contains a drain opening in combination with an outlet element rising centrally from the bottom of the bowl, a whirl-promoting tuyère occupying the top of said bowl and forming a fluid inlet, a vortex-defeating cone associated with said whirl-promoting tuyère opening toward said outlet, and an inwardly and downwardly pitched whirl-damping flange positioned above the groove in its bottom and terminating short of and below the top of said outlet element.

7. A non-rotative centrifugal fixture adapted to separate entrained substances from fluid moving therethrough and comprising a separating chamber which is open at the top and has an annularly grooved bottom which contains a drain opening in combination with an outlet element rising centrally from the bottom of the bowl, a whirl-promoting tuyère occupying the top of said bowl and forming a fluid inlet of greater effective area than said outlet, vortex-defeating means associated with said whirl-promoting tuyère, and an inwardly and downwardly pitched whirl-damping flange positioned above the groove in its bottom and terminating short of and below the top of said outlet element.

8. A non-rotative centrifugal fixture adapted to separate entrained substances from fluid moving therethrough and comprising a separating chamber which is open at the top and has an annularly grooved bottom which contains a drain opening in combination with an outlet element rising centrally from the bottom of the bowl, a radial whirl-promoting tuyère occupying the top of said bowl and forming a fluid inlet of greater effective area than said outlet, and opening toward said outlet, a vortex-defeating cone associated with said whirl-promoting tuyère, and an inwardly and downwardly pitched whirl-damping flange positioned above the groove in its bottom and terminating short of and below the top of said outlet element.

9. A non-rotative centrifugal fixture adapted to separate entrained substances from fluid moving therethrough and comprising a separating chamber which is open at the top and has an annularly grooved bottom which contains a drain opening in combination with an outlet element rising centrally from the bottom of the bowl, a barrel-shaped whirl-promoting tuyère occupying the top of said bowl and forming a fluid inlet of greater effective area than said outlet, and opening toward said outlet, a vortex-defeating cone associated with said whirl-promoting tuyère, and an inwardly and downwardly pitched whirl-damping flange positioned above the groove in its bottom and terminating short of and below the top of said outlet element.

In testimony whereof I have hereunto set my hand this 28th day of January, 1931.

CHARLES GILBERT HAWLEY.
